UNITED STATES PATENT OFFICE.

RAY P. PERRY, OF MONTCLAIR, NEW JERSEY, ASSIGNOR TO BARRETT MANUFACTURING COMPANY, A CORPORATION OF WEST VIRGINIA.

PROCESS OF JOINING SHEETS OF COMPOSITION ROOFING.

1,241,146.

Specification of Letters Patent. Patented Sept. 25, 1917.

Application filed March 24, 1915. Serial No. 16,581.

To all whom it may concern:

Be it known that I, RAY P. PERRY, a citizen of the United States, residing in Montclair, New Jersey, have invented certain new 5 and useful Improvements in Processes of Joining Sheets of Composition Roofing, of which the following is a specification.

This invention relates to an improved method of uniting or joining sheets of composition roofing of the class described below 10 and has for its object the production of a permanent waterproof joint in an expeditious and economical manner. Where I employ the term "composition roofing" in 15 this application I refer particularly to composition roofing made in sheet form by the process described in the copending application of James C. Woodley, Serial No. 796,143, filed October 20, 1913, and in general 20 to other composition roofings in sheet, tile or shingle form, which have bituminous or similar surfacing which becomes sticky or gummy on application of heat or a solvent and is capable of being treated by the 25 method described herein. Such composition roofing is usually made in sheets about thirty-two or thirty-six inches wide and when laid on the roof the edge of one sheet is lapped about two or three inches over the 30 next adjoining lower sheet and the two sheets are generally fastened together by nails, which at the same time fasten the sheets to the roof which is being covered. In some cases laths or other special devices are used 35 instead of nails. In some cases a gummy or sticky cement is applied to the abutting portions of the lapped sheets so as to unite them together and to prevent water from working up at the joint. For convenience, these 40 cements for the laps are usually made in liquid form so that they can be applied without heating and usually they consist of asphaltic or similar materials liquefied by a solvent which will later evaporate on exposure. It has been found difficult to apply 45 these cements without having an excess drip from the joint, making spots or blotches on the lower sheet of roofing, and discoloring same in a way which is very objectionable 50 from the point of view of appearance.

I have discovered that when using sheets of such composition roofing as have a relatively high percentage of bituminous or similar material I may form an improved 55 joint at the laps in the manner described

below. Preferably I use the composition roofing sheets described in the copending application of James C. Woodley, as mentioned above, such sheets containing fifty per cent. or upward of bituminous or other gummy waterproofing material. These roofing sheets when laid on a roof are usually lapped each over the next lower adjoining sheet in the customary manner and are or may be nailed together in position. In order to 60 unite the edges of two adjoining sheets where one is lapped over the other, instead of applying a separate liquid or other cement, I produce a cement *in situ*. I do this by applying sufficient heat to the sheet or sheets 65 at the joint so as to soften it or them sufficiently to bring the bituminous or other waterproofing material in the sheets into a sticky or gummy condition and I then bring the edges of the sheets together and employ 70 pressure in any desired manner, so as to cause the sheets to unite or to be cemented together. In applying heat to the edges of the sheets I ordinarily use an iron tool, which may be heated in any convenient manner. I may use an iron somewhat similar 75 to those employed in the laying of asphalt pavement, or I may use a tool which is heated electrically or by oil flame, or in any other convenient manner.

When applying pressure to the edge of the sheet, which is in a gummy or sticky condition, I preferably apply a so-called "wiping" pressure to the edge of the upper sheet 80 so as to cause a portion of same to be wiped down and form a gradual joint to the lower sheet.

The sheets of composition roofing as supplied in rolls are usually covered with a superficial layer of soapstone, talc, etc., to 85 keep them from sticking together. I may brush or wipe off this soapstone or similar material before heating the edges of the sheets, or I may wash or wipe it off by using a solvent of the hydro-carbon derivative 90 contained in the sheet of roofing. The solvent will also soften somewhat the edges of the sheets and may facilitate the cementing of the adjoining edges together. If I use sufficient solvent, I may in some cases cement 95 the edges of the sheets treated with the solvent by merely employing sufficient pressure without heat and my invention covers this method also.

Whether the edges of the sheet be softened 100

and brought to a sticky condition by heat or by the application of a solvent, the material of the sheets themselves is used in making the joint. Consequently the entire covering 5 of the roof is practically converted into a single sheet of uniform composition throughout; as contrasted with a number of separate sheets cemented by separate intermediate bodies of cement. When the process 10 is applied to sheets of fibrous composition of the Woodley or similar types the fibrous reinforcement is interlaced and carried practically continuously through from one sheet to the next, so as to provide a joint of the 15 same character and practically the same strength as the bodies of the sheets.

The accompanying drawings illustrate the process, Figure 1 being a section before applying heat and pressure and Fig. 2 being a 20 section after completion of the joint.

Fig. 1 shows the two sheets A, B of the fibrous composition above referred to, with the edge of the former overlapping the latter and held in place by means of nails C. 25 The parts being applied as in Fig. 1 are then heated and wiped so as to spread the edge of the upper sheet down upon the latter at the same time softening the sheets at the points of contact and causing the fibrous 30 reinforcement to be interlaced to a greater or less extent and the binding material of the two sheets to be merged, all as shown at D, Fig. 2.

What I claim is—

1. The process of joining sheets of composition roofing which consists in bringing outer surfaces of said sheets together while in a sticky condition and then applying pressure thereto and thus causing said outer surfaces to be united directly to each other without the interposition of additional cementing material. 35

2. The process of joining sheets of composition roofing which consists in bringing outer surfaces of said sheets together while in a heated sticky condition and then applying pressure thereto and thus causing said outer surfaces to be united directly to each other without the interposition of additional cementing material. 40

3. The process of joining sheets of composition roofing which consists in bringing outer surfaces of said sheets together, converting the composition in said outer surfaces to a sticky condition and then applying pressure thereto and thus causing said outer surfaces to be united directly to each other without the interposition of additional cementing material. 55

60 4. The process of joining sheets of com-

position roofing which consists in bringing outer surfaces of said sheets together, heating *in situ* the contacting portion of at least one of said sheets sufficiently to convert the composition of said outer surfaces 65 to a sticky condition and then applying pressure thereto and thus causing said outer surfaces to be united directly to each other without the interposition of additional cementing material. 70

5. The process of uniting adjoining lapped sheets of composition roofing which consists in converting the material at the edge of the upper sheet of said roofing *in situ* to a sticky condition and wiping some of said material 75 in such sticky condition into the lower adjoining sheet of the roofing so as to unite said sheets without the interposition of additional cementing material.

6. The process of uniting adjoining lapped sheets of composition roofing which consists in converting the material at the edge of the upper sheet of said roofing *in situ* to a sticky condition throughout the thickness of such sheet and wiping some of said material in 85 such sticky condition onto the lower adjoining sheet of the roofing so as to unite said sheets without the interposition of additional cementing material. 80

7. The process of covering a roof which 90 consists in applying thereon overlapping sheets composed homogeneously throughout their thickness of fibrous bituminous composition, bringing said composition in the edge of at least one of said sheets to a sticky condition 95 and then applying pressure to cause said sheets to be united directly to each other without the interposition of additional cementing material and with the fibers of one sheet interlaced with those of the next 100 so as to produce a roof covering which is of continuous fibrous bituminous character. 100

8. The process of covering a roof which 105 consists in applying thereon overlapping sheets composed homogeneously throughout their thickness of fibrous bituminous composition which is non-liquefiable by heat, bringing said composition in the edge of at least one of said sheets to a sticky condition and then applying pressure to cause said 110 sheets to be united directly to each other without the interposition of additional cementing material and with the fibers of one sheet interlaced with those of the next so as to produce a roof covering which is of continuous fibrous bituminous character. 115

In witness whereof, I have hereunto signed my name.

RAY P. PERRY.
